UNITED STATES PATENT OFFICE.

ERNEST J. BRASSEUR, OF CHICAGO, ILLINOIS, ASSIGNOR TO A. B. DICK COMPANY, OF CHICAGO, ILLINOIS, A CORPORATION OF ILLINOIS.

STENCIL-DUPLICATING MACHINE.

Application filed October 8, 1925. Serial No. 61,172.

This invention relates to stencil duplicating machines, and more particularly to rotary stencil duplicating machines, wherein a sheet of paper fed into the machine is frictionally engaged between the rotatable cylinder and a free rubber roller so as to be drawn through the machine upon the rotation of the cylinder, and to receive the impression from the stencil sheet on the cylinder. The stencil sheet is supplied with printing ink from the interior of the cylinder, wherein is disposed an ink chamber or reservoir. In one form of construction there is a sealed ink chamber within the cylinder from which ink may permeate through a diaphragm on the cylinder to an ink pad covering the diaphragm, and thence to the stencil sheet which is laid over the pad; and there is within the ink chamber a tiltable ink trough from which the operator may spill ink to replenish the stencil sheet. The rubber roller presses each paper sheet to be printed upwardly against the inked, rotating stencil sheet to cause the stencil sheet to imprint an impression on the upper surface of the paper. Very often, however, the cylinder is rotated without a sheet being interposed between the cylinder and the rubber roller, and if during such rotation the rubber roller should contact the inked stencil sheet on the cylinder, this roller would receive ink therefrom, with the result that the machine could not be used until this ink has been completely cleaned from the roller. Otherwise paper sheets subsequently passed between the cylinder and roller would receive ink on their backs from the rubber roller, and the sheets would be spoiled.

One of the principal objects of this invention is to provide in a rotary stencil duplicating machine mechanism which positively prevents the rubber roller from receiving ink from the surface of a stencil sheet on the cylinder, and at the same time operating automatically to press each sheet of paper to be printed against the rotating cylinder and inked stencil sheet thereon in such manner and with such pressure that each sheet receives the desired impression from the stencil sheet, and is positively drawn through the machine in the desired manner; and another object of this invention is to provide simple, durable and efficient mechanism of this character.

A further object of this invention is to provide improved means for obtaining proper and exact registration between the stencil sheet and each sheet of paper to be printed, so that the imprint from the stencil will be exactly in the desired location and alignment on each sheet.

Another object of this invention is to provide improved means for locating the cylinder transversely on the machine, and for preventing end play thereof.

A further object of this invention is to provide a rotary stencil duplicating machine having a readily removable cylinder and a readily removable rubber roller, and to provide simple, compact and durable means for removably securing the members in the machine assembly.

A further object of this invention is to provide improved means for attaching the inking pad and stencil sheet to the machine, which means permit the pad to be reversed endwise; which clamp the stencil sheet to the cylinder in such a way as to relieve the strain of the stencil sheet stub against the hooks therefor; and which prevent ink from going beyond the ends of the fabric of the ink pad and stencil; and another object of this invention is to provide means of this character which are simple, compact, and durable, and which are readily and easily adjustable on and removable from the machine to permit replacement of a stencil sheet and inking pad.

Another object of this invention is to provide improved means for locking the ink trough against accidental tipping, but permitting the operator to tip the trough at will without inconvenience.

Another object of this invention is to provide an improved table for sheets to be fed into the machine; and to provide a table which is collapsible to render the machine more compact for storage or for transportation; and to provide improved paper guide and registration means on the table.

A further object of this invention is to provide a rotary stencil duplicating machine which is simple, compact, and light in construction, comprising a very few number of parts; one which is convenient to operate and produces excellent results; and one which at the same time is sturdy and durable and clean.

Other objects of my invention will be in part obvious and in part pointed out hereinafter.

The invention accordingly consists in the features of construction, arrangement of parts and combinations of elements which will be described more fully hereinafter, and the scope of the application of which will be indicated in the claims that follow.

Reference is now made to the drawings, which form a part of this application, and illustrate certain possible embodiments of the invention, and in which: Fig. 1 is a top plan view of a machine embodying my invention, ready to operate, a fragment of the stencil sheet and ink pad being broken away; Fig. 2 is a side view of the same; Fig. 3 is a sectional view of the same, showing the table in collapsed position, the view being taken on the line 3—3 of Fig. 5; Fig. 4 is an enlarged section at one side of the top of the cylinder, and is taken on the line 4—4 of Fig. 5; Fig. 5 is a cross-sectional view, and is taken on the line 5—5 of Fig. 3; Fig. 6 is a sectional view of one side of the machine minus the cylinder, roller and paper table, and is taken on the line 6—6 of Fig. 5; Fig. 7 is an enlarged sectional view of the cylinder lock, and is taken on the line 7—7 of Fig. 6; Fig. 8 is a sectional view of the ink pad and its attachment plates, the sheet being broken away across the center; Fig. 9 is a sectional view of the machine minus the cylinder, roller and paper table, showing the cylinder catch in normal position, and is taken on the line 9—9 of Fig. 1; Fig. 10 is a repetition of a fragment of Fig. 9 showing the cylinder catch in retracted position; Fig. 11 is a top view of the same; Fig. 12 is an enlarged top view of the cylinder minus the cover or clamp plate; and Fig. 13 is an enlarged plan view, partly broken away, of the paper feed table folded into small size, and the adjacent parts of the machine. Similar reference characters refer to similar parts throughout the several views of the drawings.

Referring to the drawings, the machine has two side plates or brackets 20 and 21 secured together by tie-rods 22, and is provided with feet 23. Extending between these tie-rods and adjacent each side plate 20 and 21 is a web plate 24, 25.

An angular plate 26 is supported on one tie-rod 22 by means of angle brackets 27 which are secured to plate 26 and are penetrated by the rod 22. This plate 26 is also secured to the web plates 24, 25 by means of ears 28 formed on the webs and bolted to plate 26, as at 29. Plate 26 has a horizontal flange 30 which is narrower toward its forward edge, and ends near the engaging line of the cylinder 31 and the rubber impression roller 32 of the machine. This

flange 30 is positioned to direct sheets of paper into the desired engagement between the cylinder and roller to cause the sheet to be drawn through the machine and to be imprinted by the stencil sheet 33, carried by the cylinder. An angle plate 34 is secured on top of flange 30 toward each side edge thereof, and each plate 34 has a downwardly inclining metallic guide member 35, which may be integral with the plate 34, and may at its end 35' be secured between one of the webs 24, 25 and one of the side plates 20, 21. Each guide 35 overlies one edge of a sheet of paper fed across the flange 30, and these guides 35 aid in causing the sheet to be properly engaged between the cylinder 31 and roller 32 for printing and ejection from the machine. Preferably guide members 35 are slightly lower than the top of roller 32, where they pass by the roller adjacent its ends.

The rubber roller 32 is supported for radial movement into and out of contact with the cylinder 31 by being mounted on two arms 36 and 37, which at their rear ends are pivoted on the rear tie-bar 22, and there confined against axial movement on this bar by being interposed between one of the angle brackets 27 and a sleeve or collar 38 which extends to one of the web plates 24, 25. The arms may be attached to these sleeves. Each end of the shaft 39 of the rubber roll 32 has a ball race 40 which rests in a semi-circular journal seat 41 provided therefor on the ends of arms 36 and 37. Pivoted on each arm 36, 37, at its outer end, as at 42, is a lever 43, which at its upper end has a journal flange 44 movable over the ball race 40 in the seat 41 to confine the ball races at each end of the roller shaft and to prevent displacement of the roller.

Each side wall 20, 21 of the machine has a semi-circular journal seat 45 for the ends of the cylinder bearings 46, 47, and on each wall 20, 21 is a lever 48, 49, pivoted thereto and having a journal flange 50, 51, movable over the cylinder bearing when seated in the journal to prevent displacement of the cylinder.

A rod 52, rotatable in said plates 20, 21 extends across the machine, and has its central portion 53 offset or eccentrically disposed with respect to its axis and here engages the tops of arms 36, 37, which support the roller 32.

At each side of the machine there is a coil spring 54, which at one end is secured to an ear 55 on lever 48 or 49, and which at its other end is secured to a link 56. Each link 56 is secured to a flange 57 on the tail 125 of one of the levers 43.

Each arm 36, 37 has a stop lug 59 to limit rearward movement of the lever 43 thereon.

Adjustable stop plates 60 having forked ends 61 straddling rod 22 and clamped between the side plates 20, 21 and the webs 24, 25 present stop flanges 62 in the path of movement of tails 63 of levers 48, 49, to limit movement of these levers in one direction to prevent the cylinder bearings from being clamped too tightly between the seats 45 and the retainers 50 and 51. By over-tight engagement, the bearings might be distorted.

The springs 54 constantly urge arms 36, 37, and the roller 32 carried thereby to move upwardly into engagement with the cylinder. When levers 43 are moved to take retainers 44 into and out of co-operative position with respect to the seats 41, the lower end of spring 54 is taken across the pivot points 42 of these levers 43, and thus this spring resiliently holds these levers in either of these two positions of adjustment on the arms 36, 37. Similarly, when levers 48, 49 are moved to place their retaining flanges 50, 51 into or out of cooperation with seats 45, the upper ends of springs 54 move across the pivot points 64 of these levers, and thus these springs also hold these levers 48, 49 resiliently in either position of adjustment.

Preferably one of the cylinder seats 45 has a raised concentric rib 65, and the cylinder bearing sleeve 46 has a corresponding groove 66. The rib and groove are so located in the manufacture of the parts that the cylinder will be in proper and accurate transversely alignment on the machine when disposed thereon with the rib seated in the groove.

The cylinder stub shaft 67, which is rigidly secured to one wall of the cylinder, and which rotatably penetrates bearing sleeve 46, carries a collar or disk 68 which is notched to form a shoulder 69. A pawl 70 is pivoted to plate 20 to cooperate with this shoulder to prevent reverse rotation of the cylinder. A pin 71 on pawl 70 extends through plate 20 and is engaged by spring 72 to resiliently hold the pawl end against collar 68. The inner end of pin 71 seats in a slot 73 of a link 74 which is pivoted to link 56, so that when link 56 is lowered the end of pawl 70 will be drawn and held away from collar 68, but when link 56 is in raised position the pawl is pivotally movable on plate 20 toward and away from this collar, and into and out of engagement with shoulder 69.

Rod 52 is provided with a handle 75 whereby this rod may be rotated 180 degrees to move its offset portion 53 to depress the arms 36, 37, or to allow them to rise. The position of handle 75 corresponding to the lowered position of roller 32 may be designated by the word "On" marked on the web plate 24 and visible through a window 76 in plate 20, and the position of handle 75 corresponding to the raised position of

roller 32 may be designated similarly by the word "Off" visible through window 77.

Pivoted between pins or studs 80 on walls 20 and 21 is a cross-plate 81 having forwardly extending fingers 82, the ends of which are disposed over perforations 83 provided therefor in the guide plate 30. A finger or pawl 84 is secured to one end of plate 81, with its end disposed adjacent to the periphery of cylinder 31 so as to be movable into and out of a recess 85 in the cylinder to prevent rotation of the cylinder in printing direction. A spring 86 engaging finger 84 and one stud 80 resiliently urges this finger to engage in the recess 85. Also attached to plate 81 is a stop finger 88 with which cooperates a cam-lug 89 on an arm 90 of a bell crank lever pivotally mounted on plate 30. The other arm 91 of this lever has a handle 92 whereby the lever and its cam 89 may be adjusted to hold fingers 82 raised above plate 30, and to hold finger 84 away from cylinder 31. A stop lug or finger 93 on plate 81 is directed toward plate 30, and this finger by striking plate 30 limits rearward pivotal movement of plate 81, and movement of finger 84 away from the cylinder. A cam 95 is secured to shaft 52 and coacts with a finger 96 on plate 81 in such a way that when handle 75 is in "on" position finger 84 is free to engage the cylinder to prevent rotation in printing direction, and when handle 75 is in "off" position, finger 84 is held away from the cylinder, and fingers 82 are held above plate 30, out of recesses 83. Cam 95 has a shoulder 98 which strikes a stop projection 99 formed on the adjacent web plate 24.

One stub shaft 67 of the cylinder may have secured thereto a crank handle 94, whereby the cylinder may be rotated. To the other side of the cylinder there is secured a hollow stub shaft 97, which rotates in bearing sleeve 47.

In order to facilitate the feeding of sheets to the machine in the proper manner for printing, a feed table construction is associated therewith. This comprises two rectangular, flanged sheet-metal sections, 100 and 101, each substantially the width of the machine, and hinged together by simple hinges 102. The section 101, nearest the machine, has ears or lugs 103 pivoted on pins or studs 104 carried on plates 20 and 21.

The underside of section 100 has ears or lugs 105, in which is pivoted a frame 106 which forms a support for the rear of the feed table when extended. Frame 106 may comprise resilient wire so that it may be locked flat against section 100 beneath a turned-over portion 107 of lug 105, and may be locked in projecting position between an edge of this portion 107 and another turned-in portion 108, which preferably has a hooked end 109 to prevent the end of wire 130

106 from being entirely disengaged from lug 105 when it is brought around portion 107.

Section 101 has a slot 110 across the body thereof, and a channel-shaped strip 111 is secured to the under-surface of section 101 along this slot to provide an undercut channel runway for two nuts 112, the strip 111 having an opening 113 which accepts these nuts for placement in the runway. A guide for the edge of a sheet of paper is associated with each of these nuts for adjustment across the table. Each slideable guide comprises a vertical wall 114 having portions 115 resting on the section 101 and a central portion 116 engaging in the slot 110, and a horizontal portion 117 with a downwardly bent edge 118 resting on the section 101. A set screw 119 penetrates portion 117 and engages one nut 112, whereby the guide may be clamped to section 101 in adjusted position along the slot 110.

Section 100 has a similar runway formed by a similar channel member 120 secured to section 100 beneath a similar slot 121 therein. In this slot is a similar nut 122. Associated therewith is an elongated angle strip 123, to which is attached a bracket 124 having a flange 125 penetrated by a set screw 126 engaging nut 122, and whereby this bracket may be clamped in adjusted position along slot 121. Bracket 124 and plate 123 are pivotal about screw 126 to permit this plate to be clamped in various angular positions on the feed table. Plate 123 also has attached thereto fingers 127, which are so positioned that they can be interlocked beneath the horizontal portion 117 of one of the guide plates on the section 101, when the strip 123 is swung on screw 126 so as to be directed toward the cylinder. By means of strip 123 sections 100 and 101 can be locked against collapsing. Strip 123 forms a straight edge guide for one side of the sheets of paper placed on the table 100, 101, and fed to the machine. Aligning marks or perforations 128 and 129 may be applied to sections 100 and 101 to provide means for indicating and designating the alignment of strip 123 on the table.

Preferably section 100 is provided with a headed pin 130, which may be engaged in a recess 131 in one end of strip 123 so that this strip may be locked crosswise on section 100.

When sections 100 and 101 are collapsed, they may be swung upwardly against the cylinder, as shown in Fig. 3, or they may be placed in horizontal positions, as shown in Figs. 1 and 13. Section 101 is prevented from swinging lower than horizontal position by two ears 132, which are formed on web plates 24 and 25 and are positioned to engage the inner corners of this section. When collapsed and in horizontal position,

as shown in Fig. 13, the free edge of section 100 is prevented from falling downwardly by two other ears 133 formed on webs 24 and 25 and positioned to be beneath the free edge of section 100 when in this position. When collapsed and swung upwardly toward the cylinder (see Fig. 3), the table sections are prevented from contacting the cylinder or the stencil sheet or ink pad thereon by the guide members 114 coming against the rear edge of cross-plate 81.

Before passing to the operation of the machine, it may be well to describe in detail the construction of the cylinder, although the foregoing mechanism is independent of the specific cylinder construction illustrated. As shown, the cylinder includes two opposite side walls 150 and 151, having peripheral flanges 152 and 153. A sealed ink compartment is formed within the cylinder, the compartment having side walls 154 and 155, flanged at 156 and 157, and secured to flanges 152 and 153 of cylinder walls 150 and 151. Extending between walls 150 and 151, and embracing a major part of the circumference of the cylinder, is a perforated diaphragm 158, which has its side edges tightly secured between the flanges 152 and 156 on one side and between the flanges 153 and 157 on the other side. These seams or joints are leak-proof. Embracing the remainder of the circumference of the cylinder is a plate 160, the body of which is depressed below the surface of the cylinder. This plate has raised side flanges 161 and 162, flange 161 being secured to flange 156 of wall 154, and flange 162 being secured to flange 157 of wall 155, the joints being leak-proof.

The ends 163 of plate 160 are curved upwardly against the lower surface of the adjacent edge portion of the diaphragm and are secured thereto along a leak proof joint. The ends of plate 163 and diaphragm 158 establish beveled surfaces or seats 164.

Rigidly suspended from a shaft 165 journaled in bearings 166 and 167 secured to walls 154 and 155 is an ink trough 168. At one end shaft 165 extends outside of the machine, as at 169, so as to be accessible to the operator to tilt the trough and spill ink into the compartment to replenish the ink pad and stencil sheet. The extreme end of shaft 165 has a collar 170 secured thereto, carrying a depending finger 171, and a lever 172 movably interlocks at its lower end to finger 171, as at 173. Lever 172 has a perforation through which shaft 165 extends. A lug or button 174 is secured to the rear of lever 172 and a spring 175 collapsed between collar 170 and lever 172 resiliently urges lever 172 and button 174 toward the end plate 21. Lever 172 is arranged to be upright when the ink trough 168 is in untilted position, and when in this position lug 174 is disposed in a slot 176 formed in plate 21, 120

so that the shaft 165 cannot be rocked nor the ink trough 168 tilted to spill ink unless this lug 174 be withdrawn from this slot. In this manner accidental spilling of ink 5 from trough 168 is prevented, but the operator may conveniently spill the ink when he so desires. When released, the ink trough swings into untilted position and lug 174 automatically locks in recess 176. The lever 10 172 not only serves as a latch in the manner described but also serves as an operating handle whereby the ink trough may be tilted and rocked. This lever also serves as an indicator to indicate the position of the ink 15 trough.

Plate 160 is provided with a filling opening 177 and a cap 178 therefor, to permit ink to be poured into the trough 168.

Behind the diaphragm 158 is a grille or 20 grid structure 180 which aids in spreading over the diaphragm the ink spilled from trough 168.

The diaphragm 158 is covered by an ink pad, and the stencil sheet 33 is laid on this 25 pad. The ink pad comprises a sheet of suitable fabric 182 to each end of which is secured a strip of metal 183, by folding each strip 183 upon itself with an edge of the fabric within the fold, and then folding the 30 doubled portion over again in such a way that the round edge 184 of the fold will be in advance of the extreme edge 185 of the metal. In this way the fabric will bear against the round end 184 of the fold and 35 will not be cut by the extreme edge 185 of the plate, which edge might be sharp and jagged. Preferably the other edge of each metal strip is folded on itself, as at 186. The ink pad is secured to the cylinder by engaging the inner edge of the plates 183 within the grooves 187 formed by the bent edges 163 of the plate 160, or beneath a rod 188 positioned in one of these grooves, (see Fig. 3), and moving slidable latches 189 over the 40 opposite edges of plates 183. These latch plates 189 are slidably retained under straps 190 secured on the top of plate 160. Preferably the plates 183 are both alike so that the ink pad may be reversed, or turned over 45 on the cylinder. By changing the pad around from time to time its life may be extended.

Also on plate 160, near the leading edge 50 of the diaphragm, are secured hooks 191, with which the stub 192 of stencil sheet 33 may be engaged by placing the holes 193 in the stencil stub over the hooks. Both the ink pad and the stencil sheet lie across the beveled seats 164.

The ink pad and the stencil sheet are firmly clamped against these seats by a metal frame having edges 194 of complementary bevel to the seats 164 and arranged to align therewith. The frame comprises an outer 55 plate 195 conforming to the outer periphery

of the cylinder, and an inner plate 196, secured together, plate 196 having a perforation 197 to avoid interference from filler cap 178. Toward each side edge, plate 195 is formed with a depressed portion 198 and 60 with a raised flange, which is curved at each end, as at 199, and has a straight portion 200 intermediate these curved portions. On the underside of each straight portion 200 is a metal strip 201 which has a pin 202 65 extending through a slot 203 in flange 200 and there headed over. Toward its other end strip 201 carries a threaded pin 204 which penetrates a slot in flange 200 and is there engaged by a nut 205, whereby the 70 strip may be pivotally moved on its pin 202 toward and from flange 200. A spring 206 compressed between flange 200 and strip 201 urges the strip to move away from flange 200. The edges of the cylinder are formed 75 with curved portions 207 corresponding with flange portions 199, and with a straight portion 208 which seats beneath that part of flange portion 200 which is not occupied by strip 201, and with a lower straight portion 80 209 which extends between the curved portions 207, but is spaced from portion 208 to leave a recess therebetween. The frame 85 may be secured on the cylinder by loosening screws to lower strips 201 from flanges 200, and then after placing the frame upon the cylinder, sliding the strips on flanges 200 to place the ends of the strips in the recess between cylinder flanges 208 and 209. At the 90 same time perforations 210 in flanges 200 are engaged over pins 211 on cylinder flange portions 208. Now, by tightening nut 205 the strips 201 will be brought firmly against portions 208 and the frame will be clamped 95 tightly downwardly, thus clamping the 100 beveled edges 194 tightly toward the beveled edges 164 and clamping the ink pad and stencil sheet tightly therebetween. To remove this frame, it is only necessary to 105 grasp nuts 205, loosen them, slide them, with the attached strips 201 on flanges 200 to disengage the strips from beneath portions 208, and then lift the frame upwardly. The removal leaves the stencil sheet and pad readily accessible for removal or replacement, as 110 115 before described.

Preferably a lock is provided for frictionally holding the cylinder against rotation. This may comprise a case 220 on the inner side of wall 20, a plunger 221 in the case pressed inwardly by spring 222, and an arm 223 carried on the plunger and having a rubber or leather head 224 movable against the side 150 of the cylinder. Case 220 has on one wall a bayonet slot 225 120 through which rod 223 extends and whereby this rod may be locked with its head withdrawn from the cylinder.

When it is desired to put the machine to use, the table is lowered and is fully ex- 125 130

- 6
- tended (see Fig. 1) when it is desired to print large sheets, or is only partially extended (see Fig. 13) when it is desired to print post cards or smaller sized sheets.
- 5 The paper guide members are then adjusted on the table to direct the sheets in proper alignment into the machine. The manner of carrying out the above adjustments has been described above.
- 10 The ink pad and stencil sheet having been placed on the cylinder, in the manner outlined hereinbefore, and a satisfactory supply of ink having been given to the ink pad and stencil by operating lever 172 to spill ink
- 15 from trough 168, the roller handle 75 is now turned to "on" position. Now, due to detents 70 and 84, the cylinder cannot be turned in either direction, nor can the inked stencil sheet contact the roller 32. A sheet
- 20 is now fed manually along the feed table and plate 30 into the machine while the cylinder 68 is held tightly against detent 70, as by applying reverse pressure to handle 94. The forward part of the sheet will be disposed
- 25 between the finger 82 and the apertures 83 in plate 30. The handle 94 is now turned in printing direction, and by reason of the sheet holding the fingers 82 from lowering into apertures 83, the detent 84 will be held
- 30 away from the cylinder and the cylinder may be turned to draw the stencil sheet through the machine and to be impressed by the stencil sheet. After the paper leaves the machine the detent 84 will prevent a second rotation of the cylinder, unless another
- 35 sheet of paper is fed into the machine.
- Feeding each sheet to the machine while the disk 68 is drawn against detent 70, the upper margin on each sheet can be made
- 40 uniform, and the top of the printing will fall at a predetermined place on each sheet.
- If it should be desired to rotate the cylinder in the absence of sheets to be printed, it is merely necessary to turn the roller handle 75 to "off" position. This holds detent 84 retracted from the cylinder and at the same time holds roller 32 away from the cylinder so that it will not be damaged or dirtied by ink therefrom. At the same time
- 45 detent 70 is held away from collar 68. This freeing of the cylinder for rotation in the absence of paper to be printed is desirable at times when it is desired to replenish the stencil with ink.
- 50 If for any reason it is desired to allow the cylinder to rotate with the roller contacting the same, then detent 84 may be locked in retracted position by means of lever handle 92.
- 55 The cylinder may at any time be frictionally locked against rotation by means of the lock which is in casing 220 and is operable by handle 223.

The ink trough becomes locked automatically

against tilting by the automatic seating of the lug 174 in recess 176.

To remove the entire cylinder, it is only necessary to withdraw retaining hooks 50 and 51, and the cylinder is free to be lifted from its supporting structure.

To remove the rubber roller 32, it is only necessary to withdraw the retaining hooks 44, and the roller is free to be lifted from the machine.

When the cylinder is replaced, the engagement of groove 66 over rib 65 on the support effects accurate placement of the cylinder and eliminates any necessity for making other transverse adjustment thereof. The cylinder is rotatably locked in position on its support by bringing the retainers 50 and 51 over the cylinder bearing sleeves.

When the roller 32 is replaced, it automatically assumes proper position in its curved seats and between the side walls thereof. The roller is rotatably locked in position on the supporting arms 36 and 37 by bringing the retainers 44 over the ball races 40.

It will be noted that the springs 54 serve three separate functions. These springs press the roller against the stencil sheet so that the paper therebetween will be properly imprinted. These springs also hold the roller retainers 44 in either position of adjustment. These springs also hold the cylinder retaining levers 48 and 49 in both positions of adjustment.

When the machine is to be stored or transported, the table can be collapsed against the cylinder. As will be readily apparent, the machine is exceedingly simple, comprising a very few number of parts. Each part is readily accessible for repair or replacement. At the same time, the operator is not required to make fine adjustments when replacing the cylinder or roller, nor to exercise extreme care during operation.

As many changes could be made in the above construction and as many apparently widely different embodiments of this invention could be made without departing from the scope thereof, it is intended that all matter contained in the above description or shown in the accompanying drawings shall be interpreted as illustrative and not in a limiting sense.

What I claim is:

1. In an apparatus of the character described, in combination, a rotatable printing cylinder, a releasable detent for the cylinder, positively preventing rotation of the cylinder in one direction until the detent is released, and another releasable detent for the cylinder, positively preventing rotation of the cylinder in the opposite direction until this detent is released.
2. In an apparatus of the character de-

- scribed, in combination, a rotatable printing cylinder, a releasable detent for the cylinder, positively preventing rotation of the cylinder in one direction until the detent is released, another releasable detent for the cylinder, positively preventing rotation of the cylinder in the opposite direction until this detent is released, and means for locking both of said detents out of engagement with the cylinder to free the cylinder for repeated rotation in both directions. 5
3. In an apparatus of the character described, in combination, a rotatable printing cylinder, a rubber roller adjustable into and out of contact with the cylinder, adjustable 10 detent means engaging the cylinder and positively preventing rotation thereof in both directions, and means for simultaneously locking said roller out of contact with said cylinder and maintaining said detent means out of engagement with said cylinder, to free the cylinder for repeated rotation in both directions out of contact with said roller. 15
4. In an apparatus of the character described, in combination, a rotatable printing cylinder positioned to operate on sheets of paper fed thereto along a predetermined path, a detent engageable with the cylinder at a predetermined place governing the amount said cylinder may rotate in printing direction, and means actuated by a sheet of paper on a certain portion of said path to disengage said detent temporarily from said cylinder to permit revolution of said cylinder in printing direction. 20
5. In an apparatus of the character described, in combination, a rotatable printing cylinder positioned to operate on sheets of paper fed thereto along a predetermined path, a detent engageable with the cylinder at a predetermined place governing the amount said cylinder may rotate in printing direction, means actuated by a sheet of paper on a certain portion of said path to disengage said detent temporarily from said cylinder to permit revolution of said cylinder in printing direction, and means operative in the absence of a sheet of paper on said portion of said path to cause said detent to engage with said cylinder to prevent more than one complete revolution thereof in printing direction after release by the temporary disengagement of the detent. 25
6. In an apparatus of the character described, in combination, a rotatable printing cylinder, and means limiting rotation of said cylinder in one direction, said means including a pivoted finger engageable in a notch in said cylinder, a spring pressing said finger into engagement in said notch, and adjustable means for locking said finger out of engagement with said cylinder against the action of said spring. 30
7. In an apparatus of the character described, in combination, a rotatable printing cylinder, and means limiting rotation of said cylinder in one direction, said means including a pivoted finger engageable in a notch in said cylinder, and a spring pressing said finger into engagement in said notch, said finger having an extension, and means including a movable lever coacting with said extension, whereby said finger may be held out of engagement with said cylinder against the action of said spring. 35
8. In an apparatus of the character described, in combination, a rotatable printing cylinder, and means limiting rotation of said cylinder in one direction, said means including a pivoted finger engageable in a notch in said cylinder, a spring pressing said finger into engagement in said notch, and adjustable means for locking said finger out of engagement with said cylinder against the action of said spring, said means including an arm connected with said finger, a rotatable cam engaging said arm, and a handle for rotating said cam. 40
9. In an apparatus of the character described, in combination, a rotatable printing cylinder, and means limiting rotation of said cylinder in one direction, said means including a disk rotatable with the cylinder and having a shoulder, and a pivoted pawl coacting with the shoulder on said disk. 45
10. In an apparatus of the character described, in combination, a rotatable printing cylinder, and means limiting rotation of said cylinder in one direction, said means including a disk rotatable with the cylinder and having a shoulder, a pivoted pawl coacting with the shoulder on said disk, and spring means pressing said pawl into engagement with said shoulder. 50
11. In an apparatus of the character described, in combination, a rotatable printing cylinder, and means limiting rotation of said cylinder in one direction, said means including a disk rotatable with the cylinder and having a shoulder, a pivoted pawl coacting with the shoulder on said disk, spring means pressing said pawl into engagement with said shoulder, and adjustable means engaging said pawl for holding said pawl out of engagement with said shoulder against the action of said spring. 55
12. In an apparatus of the character described, in combination, a rotatable printing cylinder, and means limiting rotation of said cylinder in one direction, said means including a disk rotatable with the cylinder and having a shoulder, a pivoted pawl coacting with the shoulder on said disk, spring means pressing said pawl into engagement with said shoulder, and adjustable means engaging said pawl for holding said pawl out of engagement with said shoulder against the action of said spring, said adjustable means including a pivoted arm connected with said pawl, a rotatable cam shaft coacting with 60

said arm, and a handle for rotating said cam shaft.

13. In an apparatus of the character described, in combination, a rotatable printing cylinder, a paper feed plate adjacent the cylinder and having apertures, a pivoted plate over said feed plate and having feeler fingers movable with said plate into and out of said apertures, a detent attached to said plate and movable therewith into and out of engagement with said cylinder, to limit rotation of said cylinder when said fingers enter said apertures and to permit rotation of said cylinder when said fingers are withdrawn from said apertures.

14. In an apparatus of the character described, in combination, a rotatable printing cylinder, a paper feed plate adjacent the cylinder and having apertures, a pivoted plate over said feed plate and having feeler fingers movable with said plate into and out of said apertures, a detent attached to said plate and movable therewith into and out of engagement with said cylinder, to limit rotation of said cylinder when said fingers enter said apertures and to permit rotation of said cylinder when said fingers are withdrawn from said apertures, an arm on said plate, a rotatable cam coacting with said arm, and a handle for rotating said cam to hold said detent out of engagement with said cylinder.

15. In an apparatus of the character described, in combination, a rubber roller, pivoted arms supporting said roller, a rotatable shaft having an offset portion engaging said arms from above, spring means pressing said arms upwardly against said shaft, and a handle for rotating said shaft to rotate said offset portion to cause said arms and the roller carried thereon to raise and lower.

16. In an apparatus of the character described, in combination, a rubber roller, pivoted arms supporting said roller, a rotatable shaft having an offset portion engaging said arms from above, spring means pressing said arms upwardly against said shaft, a rotatable printing cylinder, a pivoted detent engageable with said cylinder to limit rotation thereof, an arm connected with said detent for movement therewith, a cam on said shaft coacting with said arm, and a handle for rotating said shaft to rotate said offset portion to cause said arms and the roller carried thereon to raise and lower, and to rotate said cam to permit and to prevent said detent from engaging said cylinder.

17. In an apparatus of the character de-

scribed, in combination, a rubber roller, pivoted arms supporting said roller, a rotatable shaft having an offset portion engaging said arms from above, spring means pressing said arms upwardly against said shaft, a rotatable printing cylinder, a pivoted detent engageable with said cylinder to limit rotation thereof in one direction, an arm connected with said detent for movement therewith, a cam on said shaft coacting with said arm, another detent engageable with said cylinder to limit rotation thereof in the opposite direction, a link connecting this detent with one of said roller supporting arms for movement therewith, and a handle for rotating said shaft to rotate said offset portion to cause said arms and the roller carried thereon and said link to raise and lower, and to rotate said cam to permit and to prevent said detent from engaging said cylinder, whereby said cylinder is freed for repeated revolution in both directions while said roller is held out of contact therewith, and is held by said detents against rotation in either direction while said roller contacts said cylinder.

18. In an apparatus of the character described, in combination, a rubber roller, pivoted arms supporting said roller, a rotatable shaft having an offset portion engaging said arms from above, spring means pressing said arms upwardly against said shaft, a rotatable printing cylinder, a pivoted detent engageable with said cylinder to limit rotation thereof in one direction, an arm connected with said detent for movement therewith, a cam on said shaft coacting with said arm, another detent engageable with said cylinder to limit rotation thereof in the opposite direction, a link connecting this detent with one of said roller supporting arms for movement therewith, and a handle for rotating said shaft to rotate said offset portion to cause said arms and the roller carried thereon and said link to raise and lower, and to rotate said cam to permit and to prevent said detent from engaging said cylinder, whereby said cylinder is freed for repeated revolution in both directions while said roller is held out of contact therewith, and is held by said detents against rotation in either direction while said roller contacts said cylinder, and means actuated by a sheet of paper fed to the machine for releasing the cylinder for rotation in printing direction while said roller contacts the cylinder.

This specification signed this 5th day of October, 1925.

ERNEST J. BRASSEUR.
